UNITED STATES PATENT OFFICE.

WILLIAM E. KELLY, OF NEW BRUNSWICK, NEW JERSEY.

GRATE.

SPECIFICATION forming part of Letters Patent No. 367,147, dated July 26, 1887.

Application filed July 24, 1886. Serial No. 203,919. (No model.)

To all whom it may concern:

Be it known that I, WILLIAM E. KELLY, of New Brunswick, in the county of Middlesex and State of New Jersey, have invented a certain new and useful Improvement in Grate-Bars, of which the following is a specification.

I will describe grate-bars embodying my improvement, and then point out the various features in the claims.

10 In the accompanying drawings, Figure 1 designates a partly sectional side view of a grate-bar embodying my improvement. Fig. 2 is a transverse section of the same. Fig. 3 is a partly sectional side view of a grate-bar 15 of somewhat modified form embodying my improvement. Fig. 4 is a transverse section of the latter.

Similar letters of reference designate corresponding parts in all the figures.

20 Referring first to Figs. 1 and 2, A designates the grate-bar, which may be flat-sided in the main, but has the upper portion somewhat widened with relation to the main portion and curved convergently to a central point 25 or apex. The curved portion a' , at one side of the upper portion of the bar, terminates in a shoulder at its lowest extremity. The other curved portion, a'' , extends in a continuous curve until it reaches the flat lower portion 30 of the bar, with the exception that in it is a groove, a'' , which extends lengthwise of the bar. The bottom of the bar may be arched, for the purpose of strengthening it.

B designates leaves, some of which have 35 their top surface formed of central flat portions and connecting arc-shaped end portions, while others have a continuous arc shape throughout. These leaves B have openings corresponding in shape to the upper curved 40 portions, a' a'' , of the bar A, convergently curved to a central point. The side b' of the opening of the leaves, corresponding to the curved side portion a' of the bar A, has at the lower extremity an inwardly-extending portion, b'' , 45 forming a fulcrum piece or pivot and adapted to fit under the shoulder, which is formed at the lower extremity of the curved side portion a' of the bar A. The curved side portion a'' of the bar A and also the side b'' of 50 the opening of each leaf B are curved concentrically to the point upon which the leaves may be rocked or swung when the inwardly-

extending portion b'' of the leaf is fitted in its place under the shoulder formed at the lower extremity of the curved side portion a' of the bar A. Consequently when this inwardly-extending portion is fitted in its place the leaf may be swung over the top of the bar A until the curved portion b'' of its opening rests against the curved side portion a'' of the bar. 55

In the curved side portion b'' of each leaf opposite the groove a'' is a groove, b'' . These two grooves, a'' b'' , together form a cavity for the reception of a locking-piece, C, here shown as made in the form of a rounded pin. 65 This locking-piece is inserted endwise after the placing of the leaf upon the bar. It may not only serve to lock a single leaf of the bar, but may be made long enough to extend through the entire series of leaves arranged 70 upon the bar. It may be made in the form of a ring of stout wire extending through but a single leaf, and when made so as to fasten but one leaf to the bar it will have the advantage of affording facility for the detachment 75 of a single leaf without disturbing others, because it can be cut away so as to disengage the leaf through which it passes without having any effect upon the other leaves.

Each of the leaves shown has a flange, b'' , 80 at one side around its opening, which fits the bar A. If a single locking-piece is to be used for each bar, it may be found advantageous to omit the flange b'' of each leaf opposite its notch or groove b'' , in order that access may 85 be had to the locking-piece. The flanges b'' form spacing-pieces, keeping the leaves properly located with respect to each other. They also protect the top of the bar A, where otherwise it would be exposed, and prevent its 90 being subjected to excessive heat, which might have a tendency to produce warping.

In the example of my improvement shown in Figs. 3 and 4 the bar A is the same as that previously described, except that its curved 95 portion a'' has not any groove a'' formed in it; but in lieu of that it has extending from it at intervals a number of lugs, a'' , having hooked lower ends. The leaves B in this example of my improvement are formed like those heretofore described, except that they lack the 100 grooves b'' and have at the sides of their openings extensions b'' , provided with holes b'' . When one of these leaves B has been swung

into place, its extension b^6 will be adjacent to one of the lugs a^6 of the bar A, and its hole b^7 will be in line with the lower hooked end of such lug a^6 . A locking-piece, C, consisting of a pin or ring or analogous device, may be inserted into the hole b^7 and under the hooked lower end of the lug a^6 , whereupon it will secure the leaf in position. In this example of my invention, as well as in the first described, 15 a locking-piece may be employed for each leaf or for the whole series of leaves.

In each example of my invention the bar A will preferably have end flanges, a^{10} , which will preclude endwise movements of the leaves 15 B, and these will be provided with trunnions, if the grate-bar is to rock.

What I claim as my invention, and desire to secure by Letters Patent, is—

1. The combination, with a grate-bar having the upper portion of its sides convergently curved, a shoulder on one of its sides, and a groove or notch on its other side, of a leaf having an opening corresponding in shape to the convergently curved upper portion of the bar,

and being also provided on one side with an inwardly-extending portion adapted to be placed against said shoulder, so that the leaf may be swung over the top of and fit upon the top of the bar, and upon the other side with a groove or hole, and an independent locking-piece for securing the leaf to the bar inserted in said groove, notch, or hole lengthwise of the bar, substantially as specified.

2. The combination, with a grate-bar having a shoulder on one of its sides and a groove or notch on the other side, of a leaf provided on one side with an inwardly-extending portion adapted to be placed against said shoulder, so that the leaf may be swung over the top of the bar and upon the other side with a groove, notch, or hole, and an independent locking-piece for securing the leaf to the bar inserted in said groove, notch, or hole lengthwise of the bar, substantially as specified.

WILLIAM E. KELLY.
